UNITED STATES PATENT OFFICE

JEAN A. H. BARKEIJ, OF LOS ANGELES, CALIFORNIA

INTERNAL COMBUSTION ENGINE

Application filed December 26, 1925. Serial No. 77,803.

My invention relates to internal combustion engines and more particularly to sleeve-valve internal combustion engines.

My primary object is to provide a sleeve-valve internal combustion engine, of which one of the sleeves (preferably the one nearest to the piston) is cooled internally by some fluid, in order to obtain a better cooling of the piston and the sleeves.

10 My second object is to provide a sleeve, that can be machined from a solid piece of steel tube; the other sleeve or sleeves, the cylinder head, the cylinder wall can be likewise machined from solid pieces of steel.

15 My third object is to cool the sleeve equally over its entire surface, by decreasing the inside diameter of the oil passages above and below the inlet and exhaust slot in the sleeve compared with the diameter of the oil passages in the connections between the upper and lower part of the sleeve.

20 My fourth object is to combine maximum strength and cooling surface with a minimum of weight of the sleeve in order to decrease vibration.

25 My fifth object is to prevent leakage along the sleeves towards the explosion chamber, exhaust and inlet manifolds by increasing the diameter of the upper end of the sleeve, providing this enlargement with an oil ring, by 30 providing the detachable head with oil rings, and the sleeve with horizontal oil holes in order to eliminate an eventual abundance of oil which might pass the oil rings on both sides of the sleeve.

It is especially advantageous to prevent too much oil from entering the piston chamber via the inlet ports in the sleeves, due to the suction therein (piston chamber) by applying 35 suction on said inlet side to counteract said first suction, thereby preventing excessive smoking and carboning up of the combustion chamber.

40 My sixth object is to provide an oil reservoir on top of the water reservoir, in order to cool the oil by the adjacent water jacket.

45 My seventh object is to decrease the entire engine length by eliminating the water spaces, thereby decreasing the length of the crankshaft, camshaft and crankcase.

50 My eighth object is to provide such a construction that the oil-reservoir cover, the water space, the detachable cylinder heads are connected to the cylinder walls with a single row of bolts.

55 My final and general object is to provide a double cooling system for internal combustion engines, more especially of the constant volume type, the gasoline or petrol motor. The explosion space receives a much greater 60

quantity of heat from the working fluid than the expansion space, especially in the latter type of engines. The explosion space should be cooled much more intensively than the expansion space on its outside surface, as the 65 inside of the explosion space receives much more heat. To keep the temperature of the quantity of fluid, cooling the second space, at a higher temperature, the two quantities are permanently separated by walls. One 70 of the quantities of cooling fluid can be more intensively cooled by an outside cooling apparatus, not forming a part of the engine proper, although this condition is immaterial to the system proposed. This system will 75

in general improve the fuel consumption of the engine and can be used directly to rectify the condition of the oil, if this fluid is used to cool either the expansion or the 80

explosion space.

It is also my final and general object to cool the oil, used to lubricate the moving parts in the crankcase, by means of the temperature of the water, which is used to cool the cylinders. The great advantage of this system is, that it is not necessary to lead the oil 85

to a separate cooler with all its attendant inconveniences. In the present system the oil is cooled directly by the water, said two quantities of fluid only separated from each other by a single metal wall, so that the heat exchange can be made very effective. This exchange can be increased by increasing the surface of the wall separating said two quantities of liquid, and by the use of metals of high conductivity between the two quantities of fluid. The water is cooled in an outside standard radiator, as is well known in the art, so that said radiator regulates also directly and substantially the heat of the lubricating fluid 95

100

lubricating the moving parts of the engine. Especially at high speeds when the pressures in the modern internal combustion engine are very high, the temperature of the oil in the present engine, when far below the ordinary temperature in the carters of modern motors, will increase or rather retain the lubricating qualities of the oil, especially the viscosity thereof. When said oil had to be conveyed 10 back and forth to a radiator like the water, cooling the cylinder block, leakage is bound to occur much sooner than in the present system, in which the oil is kept in a closed and short circuit. The water in the present engine 15 may, of course, also cool the outside walls 1 and 1, in order to cool the oil some more, before reaching the crankcase.

Considering the metals and liquids mostly used in the construction of internal combustion engines of both types under consideration, specific heat and specific conductivity of cast iron (steel), pure aluminum, oil and water are not identical.

The specific heat at about 100° C., for said materials is in the order enumerated, aluminum and water have greater specific heat than respectively iron and oil.

For conductivity that of aluminum is greater than that of cast iron, though its density is far less than that of cast iron. That of water less than that of oil.

For the method of cooling explained the combination of aluminum and water will conduct more heat away from the gases during compression and combustion than the combination of aluminum and oil, or cast iron with water or oil. The conductivity of gases is still poorer than that of liquids, which are poorer conductors than solids. Therefore, if 40 air cooling is used (air being a fluid) the walls of the combustion space should be of aluminum and those of the expansion space of cast iron or steel, in which case a greater amount of heat is conducted away from the 45 working fluid in the combustion chamber than in the expansion chamber per unit of surface, and per unit of thickness of the walls of said chamber, per unit of time, per unit of temperature difference between the respective 50 materials (gases and chamber-walls).

Alloys of aluminum may have, however, specific heat values and conductivity values which are vastly different from aluminum as an element. Further, the specific heat and specific conductivity varies considerable with the temperature of said materials also. Therefore, the normal operating temperature of the walls of the combustion chamber and expansion chamber should be considered 55 as being substantially below 100° Celsius under average conditions.

The specific conductivity of the metals of the walls of these two chambers at said temperatures and the specific heat of the cooling 60 materials, solids, liquids or fluids at said

temperatures, cooling said first metals should be primarily considered in the construction of a given land-, water-, or air-engine in order to apply the proposed cooling system (thermodynamical-efficiency) to its greatest 70 advantage.

Specific heat is here considered the quantity of heat necessary to produce a temperature change, in unit mass, measured in C. G. S. units, as calories per gram per degree centigrade. A certain material has greater specific heat value if one calorie causes in said substance a smaller raise in temperature (here at average working temperatures of said internal combustion engines). Aluminum and 80 water have a greater specific heat than cast iron and oil respectively.

Specific conductivity is the quantity of heat in calories, which is transmitted, across an area of one square centimeter, through a 85 thickness of one centimeter, per second, when the temperature difference is one degree centigrade. Aluminum (pure) has greater conductivity than cast iron at about 100° Celsius, and water has less conductivity than lubricating oil at temperatures below, or closely 90 around, 100° Celsius.

The specific heat of pure aluminum approaches that of cast iron pretty close at high temperatures. Therefore, in a water-cooled engine there is greater difference in the application of these two different metals than in air-cooled engines. Therefore, the application of two solids (two different metals), one above the other, may produce the above explained cooling system just as well, with or without the application of liquids or fluids on one of said two metals.

Referring to the drawings which accompany this specification and form a part 105 thereof,

Fig. 1 is a sectional vertical view of a sleeve valve cylinder, a sleeve with vertical and horizontal oil passages, a piston, a water-cooled cylinder head, an oil reservoir on top of the 110 water space above the cylinder head.

Fig. 2 is a similar horizontal view of the inner sleeve on the line S1 of Fig. 1.

Fig. 3 is a sectional horizontal view of the same sleeve on the line S2 of Fig. 1.

Fig. 4 is a similar view of the same sleeve on the line S3 of Fig. 1.

Fig. 5 is a sectional vertical view of the inner sleeve on the line S4 of Fig. 2, between the lines S5 and S6 of Fig. 1, showing the 120 horizontal oil passages above and below the inlet and exhaust ports.

Fig. 6 is a vertical elevation view of the inner sleeve on the circular section line of 125 Fig. 4, showing the vertical and horizontal oil passages and the walls between these passages, the direction of the oil flow in gravitational direction. This drawing is purely diagrammatic, the surface of the sleeve be- 130

ing partially rolled out in the plane of the paper on the circular line S7 of Fig. 4.

In Fig. 1, 1 is the cylinder wall, 2 is the piston, 3 the connecting rod, 4 the inner sleeve, 5 the outer sleeve, 6 the detachable cylinder head with an upward extension 6a and a water space 8. 7 is the cover of the water space above the cylinder heads, 9 is the oil reservoir (oil space) above the water space and the cover 7, 27 is the cover for the oil space. 10 are the oil passages, which lead from the reservoir 9, through the cylinder cover 7, the detachable cylinder head 6, the intermediate connecting plate 10a, towards the annular space 11 above the inner sleeve 4. 12 are rings to decrease the inside diameter of the oil passages 13b in the sleeve 4. 4a is the increased diameter of the top of the sleeve, 4b the oil ring therein, 14 is the inside, 15 the outside of the sleeve 4. 20 is the upper edge, 21 the lower edge adjacent to the exhaust port 24 and the inlet port 25 of the inner sleeve 4. 22 are the rings which will be explained later. 23 are the horizontal oil passages above and below the ports in the sleeve 4. 24 is the exhaust port, 25 the inlet port in said sleeve. 26 the exhaust port in the outer sleeve, 27a the inlet port. 28 is the exhaust manifold, 29 the inlet manifold. 30 is an oil pipe to eliminate superfluous oil passing the oil rings 4b and the oil rings 4c. This suction pipe connects in the cylinder wall first with the annular space 31 above the outer sleeve and below the increased diameter 4a of the inner sleeve, and from there through the oil holes 13d in the inner sleeve 4, with the inside bore of said sleeve and the outer surface of the detachable head carrying the oil rings 4c, 6b are the junk rings. It is understood that the detachable head may be provided with oil grooves between the two latter types of rings communicating with the oil holes 13d of the inner sleeve, to abduct the oil passing said rings 4c.

32 is a pump which carries the oil from the crankcase through the pipe 33 towards the oil space 9.

In Fig. 2 the same numbers 4, 4a, 4b, 12, 13, 13a, 13d, 14, 15 represent the same parts as in Fig. 1.

The oil rings may be in multiple. The space 31 is not necessary if a single sleeve is used.

The nonlubricating cooling fluid is placed within the lubricating fluid for the following reasons.

1° The heat in the oil can radiate towards the air and towards the water.

2° The water can be better transferred to an outside cooling apparatus.

3° Lost water can be replaced cheaper and almost anywhere.

4° Water-tight connections are easier to make than oil-tight connections.

5° The circular passages around the cylinder

have two distinct advantages above jacket cooling. The resistance against internal pressures is increased, the cooling capacity increased. These two advantages are of increasing importance, if the cylinder diameter increases. Horizontal circular passages might have the same advantage in said second respect, but is inferior in said first respect.

Equally in Fig. 3 the same numbers represent the same parts; it represents a horizontal section of the sleeve a little lower, than Fig. 2, but above the ports. The diameter of the holes shown in this Fig. 3 are in proportion equal to those shown in Fig. 1 at the top end, without the inserted tubes 12, and equal to those at the bottom end of the sleeve. It is understood that the circular holes can be made of uniform size for reasons of economy and strength for longitudinal and circumferential stresses on account of internal pressures.

In Fig. 4, 16, 17, 18, 19 are the bridges in the sleeve adjacent to the inlet and exhaust port, connecting the upper part above the ports with the lower part of the sleeve, below the ports. These bridges are provided with oil passages, which are a continuation of the oil passages 13b in the upper part of the sleeve and convey the oil from the upper part of the sleeve to the lower part.

In Fig. 5, 23 is a horizontal oil passage connecting all the vertical oil passages above the exhaust and inlet port, 22 are rings which cover these horizontal oil passages.

The oil passages 13b, shown in Fig. 2, end into the horizontal passages 23. The oil passages 13c, are not shown in Fig. 5, but they end also into these passages as is shown in Fig. 6.

In this Fig. 6 the outer surface of the inner sleeve, on the lines S7 of Fig. 4, is shown and the rings are removed in order to show the horizontal oil passages 23, and the vertical passages, 13b and 13c, above and below the exhaust port 24. The intermediate walls 13a and the upper and lower edge 20 and 21 are shown, 17 is the bridge with a single oil passage, connecting the upper part with the lower part of the sleeve. The flow of the oil is indicated by arrows. The surface of the section on the line S7 is rolled out in the plane of the paper, the drawing is not perspective.

22 are rings which cover the horizontal oil passages 23, machined in the body of the sleeve, in order to connect all the vertical passages in the upper and lower part of the sleeve. The vertical oil holes 13b going straight through the connection 16, 17, 18, 19 can be drilled with a larger diameter than the oil holes 13c, in order to obtain equal cooling of the sleeve; the aggregate area of the oil holes at the top of the sleeve should be approximately equal to that of the area of the oil passages going through the bridges 16, 17, 18, 19. The oil holes 13b can be drilled

at a larger diameter than the other ones and consequently the top end of the oil holes 13b has to be restricted to make the area of the top end of all the oil passages equal to the sum of the areas of the oil passages in 16, 17, 18, 19. The vertical oil holes below the ports (see S8 in Fig. 1) can be drilled uniform, their area being equal to the area of the oil holes in 16, 17, 18, 19.

10 The function of the oil cooling needs little further explanation. The oil has to be pumped from the crankcase to the oil reservoir 9 and will disappear in a continuous stream downwards through the holes 10 in the oil cover 7, plate 10a, and through the upper part of the detachable head 6, through the annular space 11, to the oil holes 13b and 13c of the sleeve. The oil leaves at the bottom of the sleeves and lubricates connecting rods, crankshaft and eccentric shaft. It might be advisable to decrease gradually the diameter of the passages 13 towards the middle of that part of the sleeve, which is above the bridges and to increase the diameter towards that part of the sleeve above the ports. This arrangement might be even better, to obtain an equal cooling of the entire sleeve. It is considered to be sufficient to show the restrictions 12 in Fig. 2 of the top end of the oil holes 13b, equalizing the diameter of all top ends. This construction would be more expensive. The construction of the entire sleeve is so that it can be machined from a solid piece of steel, as the outer sleeve, cylinder head and cylinder wall, thereby obtaining material with the same expansion coefficient and cheap to manufacture. The exhaust and inlet manifold, the cylinder head 27, oil cover 7 have to be cast of any suitable material. The cylinder head 6, cylinder head cover or oil cover 7 are provided with cooling ribs to increase the heat exchange between oil and water. The rings 22 can be made so closely fitting that little oil will escape, but they can be welded to the body of the sleeve afterwards, to increase the strength of the sleeve at that point. The edges 20 and 21 have to be comparatively thick to prevent too great a weakness of the sleeve at that point, if the rings are not welded to the body of the sleeve. The rings can be stepped as shown, to diminish oil leakage.

15 The oil pipe 30 serves to eliminate an eventual surplus of oil passing the packing ring 4b in the sleeve and the oil-packing rings 4c in the cylinder head. Oil holes through the sleeve 13d, between the smaller holes 13c, perpendicular to each other, carries the superfluous oil through the sleeve from the inside to the outside of the sleeve towards the annular space 13 above the second outer sleeve, whence it is carried by suction to the same pipe 30.

20 The upper oil reservoir cover 27, the cover 7, the plate 10a, between the oil and water space,

may also be provided with cooling ribs on both sides. The cylinder head 6 can be connected to the cylinder wall 1 by means of two rows of bolts 28a and 28 around the cylinder, and will form together a solid mass to withstand the explosion pressure and lateral thrust of the piston.

25 The cylinder head 6 has an upward extension 6a, the nuts 11a are tightened before the nuts 28 and after the nuts 28a, and hereafter a tight joint is made between 6a and the cover 27 by the nuts 11b, after the nuts 28 are tightened.

30 33 is an oil pipe leading from the oil reservoir 9 towards the pump 32, and from there to the oil sump in the crankcase. The oil is pumped upwards. If the motor stops all oil will drain from space 9. It is, of course, understood that the suction on pipe 30 can be produced by the engine itself, as for instance at the manifold, but any other source will do.

35 Though the annular space 31 surrounds the entire inner sleeve, it is preferred to place it exclusively at the inlet side, as the suction of the piston during the inlet period and other periods of four-stroke cycle is more than sufficient to draw oil past the rings 4a and 4c, and through the inlet ports 27a and 25 in the sleeves into the combustion chamber, which causes excessive smoking, as in standard Knight engines, without the present system of cooling. Therefore, it is understood that this arrangement may be applied on Knight engines without this cooling system, having the sleeve valve movement and piston movement, as proposed in my previous application of 26 March, 1925, No. 18,456, Patent 1,666,160, in which case it would be correspondingly advantageous to place the suction pipe 30 at the inlet side, but below the ports, as, of course, here more oil is naturally drawn up by the piston suction from the lower end of the sleeves, if no oil is supplied at the upper end. This arrangement will prevent here, equally of course, excessive smoking and excessive accumulation of carbon, which is particularly annoying in this type of engine as demounting and cleaning is much more expensive in this type of engine due to its particular construction, as is well known in the art.

40 In the present arrangement of the inlet port 27a in the outer sleeve, below the inlet port in the cylinder, equal to the arrangement as shown in Figs. 1-5 of said patent, the suction port 30 is placed above the ports, as the most oil leaks from above instead of from below, as in standard engines. If said arrangement is applied on a standard engine, without the present cooling system, the pipe 30 should be, of course, below the inlet ports in the outer sleeve to prevent oil reaching these ports before they communicate with the piston chamber. If the movement of Figs. 6-9 of said

patent is applied, the same position would be preferable, though the inlet port moves above the inlet ports in the cylinder, like in standard engines.

5. In standard engines, most of the oil comes from the lower end of the sleeves. Therefore, the direction of flow of the superfluous oil is a first consideration and the position of the inlet port 27a in the outer sleeve is of 10 minor importance.

However, a second important consideration is where the piston pressure comes. This pressure squeezes the oil between the cylinder and outer sleeve and between the inner 15 and outer sleeve towards the ports in the sleeves and downwards towards the crankcase. If the piston pressure comes, as shown in all of said figures in said Patent 1,666,160, on the inlet side (due to the particular direction 20 of rotation of the crankshaft) then the oil is pressed on the inlet side, and abundance of oil should be removed even more advantageously in such an arrangement. In standard Knight engines, the piston pressure 25 is always on the exhaust side, but if the abundance of oil is removed from said inlet side, there is even less objection in exerting the piston pressure on the inlet side, as here proposed in combination with a new cooling 30 system, for the sake of compactness and simplicity. It should therefore be clearly understood that these two arrangements are more or less connected with each other, but the suction arrangement is, of course, applicable 35 with all its very important advantages on all standard arrangements, and those of Patent 1,666,160. It is, of course, understood that the method of cooling the lubricating oil, as shown for a sleeve valve engine, may 40 be applied also equally on a poppet valve engine or any other type of engine, with such changes of design as logic, skill and judicious choice may suggest to a skilled engineer or 45 mechanic. The same reasoning obtains for the removal of oil from the sleeves at the inlet sides thereof.

I claim:

1. In an internal combustion engine, the combination of a cylinder, a detachable head 50 for said cylinder, containing a space for a nonlubricating fluid and a separate space for a lubricating fluid, said spaces adjoining each other in said detachable head, substantially as shown and passages for said lubricating 55 fluid in the cylinder wall.

2. In an internal combustion engine, a cylinder having a combustion space, an expansion space and a piston reciprocating in the latter space, a cooling fluid circulating around 60 the entire combustion space, a second cooling fluid circulating around the entire expansion space, said cooling fluids separated from each other by walls in said engine.

3. In an internal combustion engine, the 65 combination of a cylinder, a working piston,

a working fluid expanding in said cylinder, a cooling liquid surrounding and adjacent to said cylinder, another volume of cooling liquid separated from the first fluid by walls, and not adjacent to said cylinder, said second volume of fluid cooling said first volume of fluid.

4. In an internal combustion engine, the combination of a cylinder, a working piston, 70 a working fluid expanding in said cylinder, a nonlubricating fluid circulated to and from the engine to and from a cooler, a lubricating fluid circulating from and to the crankcase, and from and to said cylinder, said first fluid cooling said second fluid, said second 75 fluid a part of said cylinder.

5. In a sleeve valve internal combustion engine, the combination of a cylinder, a re-entrant head and reciprocating piston within 80 at least one concentric sleeve valve in said cylinder, an oil lead connected with the inner surface of said cylinder at a point between the upper end of said sleeve in its lowest position and the lower end of said sleeve in its highest position, said oil lead connected with 85 a source of suction to remove oil from between said cylinder and said sleeve.

6. The combination of claim 5 in which 90 said oil lead is connected with said cylinder at the inlet side of said cylinder.

7. In a sleeve valve internal combustion engine, having a cylinder, two concentric sleeves in said cylinder, a reciprocating piston in the inner one of said sleeve, an oil lead 100 connecting with the inlet side of said cylinder to remove oil from the surface of contact between the cylinder and the outer sleeve, and from the surface between the sleeves, by means of a source of suction.

8. The combination of claim 7 in which a 105 reentrant head is located in said inner sleeve, oil passages in said inner sleeve between the outer and inner surface of said inner sleeve, to connect said suction source to the inner surface of said inner sleeve, the outer surface 110 thereof and the adjacent surface of said reentrant head.

9. In an internal combustion engine, the combination of a cylinder having inlet and 115 exhaust ports opposite each other and extending only around a part of its circumference, sleeve means in said cylinder controlling said cylinder ports, said sleeves having also inlet ports opposite exhaust ports corresponding to those in said cylinder; means to move said sleeve means; means to lubricate said cylinder, said sleeve means, and a piston reciprocating in said sleeve means; additional means to remove lubricant from said sleeve means by a source of suction attached to said cylinder, and having communication with the 120 surface of contact between said cylinder and outer sleeve, between said outer sleeve and inner sleeve, and between said inner sleeve and said parts within said sleeve.

120

125

125

130

10. The combination of claim 9, in which said source of suction is located at the inlet side of said cylinder and sleeve means, at a point located between the top and bottom 5 ends of said sleeve means in any position during the operation of said engine, said removal of said lubricant being intermittent. 70
11. In combination with a cylinder and a combustion chamber of an internal combustion engine, a liquid in contact with said combustion chamber and a different liquid in contact with said cylinder, said two liquids in direct heat-conductive relation with each other, but separated from each other by metal 10 walls. 75
12. In combination with a cylinder ending in a combustion chamber of an internal combustion engine, a jacket for containing a liquid in contact with the upper end of said cylinder, a second jacket for containing a liquid in contact with the lower end of said cylinder, said latter jacket not adjacent said combustion chamber but adjacent said cylinder and cooling also directly by conduction 20 of the liquid in said first chamber. 80
13. The combination of claim 12 in which the heat exchanges between said liquids and said jackets is increased for at least one of them by the use of a metal having a higher 25 heat conductivity than the metal of the other jacket. 85
14. In an internal combustion engine the combination of a cylinder, a piston reciprocating in said cylinder, valvular means to introduce and exhaust gases from said cylinder; said cylinder cooled by a volume of liquid; said valvular means lubricated by a volume of lubricating liquid; said first volume cooling said cylinder in a jacket around 30 said cylinder, said second volume of lubricant cooled by said first volume of liquid in a space adjacent said cylinder and said first jacket; means to circulate said lubricant from said space to the crankcase of said cylinder 40 and from said crankcase to said space; said lubricant lubricating the moving parts in said crankcase, and said valvular means outside said crankcase. 90
15. In combination with a cylinder and a combustion chamber, of an internal combustion engine, the application of fluids of greater specific heat on the walls of said combustion chamber than on the walls of said cylinder, said liquids being contained in separate chambers. 100
16. An internal combustion engine, comprising a cylinder, a working piston therein, a working fluid expanding in said cylinder, the space within said cylinder, confined by walls, 30 directly cooled by water at its upper end, by a lubricant at its lower end, said first fluid exchanging heat with said lubricant without immediate contact of said liquids with each other, said liquids being in separate chambers. 105
17. An internal combustion engine, com- 65 110
- prising a cylinder, a working piston in said cylinder reciprocating by the force of a working fluid therein, the space within said cylinder, confined by walls, cooled at its upper end by a liquid, said cylinder also cooled by a lubricating liquid in a jacket adjoining said cylinder, said lubricant circulating to and from said cylinder, said oil jacket being adjacent to said water jacket; said water exchanging with said oil by conductivity, means to circulate said oil from said cylinder to the moving parts in said crankcase and reversely; said two liquids being in separate jackets adjacent each other. 115
